UNITED STATES PATENT OFFICE.

SAMUEL E. WINDER, OF CHICAGO, ILLINOIS, ASSIGNOR TO NOVELTY CUP & CONE COMPANY, OF CHICAGO, ILLINOIS, A CORPORATION OF ILLINOIS.

DESIGN FOR AN EDIBLE DESSERT-CUP.

57,177.

Specification for Design.

Patented Feb. 22, 1921.

Application filed February 2, 1920. Serial No. 355,872. Term of patent 7 years.

To all whom it may concern:

Be it known that I, SAMUEL E. WINDER, a citizen of the United States, residing at Chicago, in the county of Cook and State of Illinois, have invented a new, original, and ornamental Design for Edible Dessert-Cups, of which the following is a specification, reference being had to the accompanying drawing, forming part thereof.

Figure 1 is a perspective view of an edible dessert cup, showing my design; Fig. 2 is a sectional plan view of the cup along the line 2—2; and Fig. 3 is a fragmental sectional view of the cup.

I claim:

The ornamental design for an edible dessert cup, as shown.

SAMUEL E. WINDER.
